ROBERT E. LANKFORD, OF PITTSBURGH, PENNSYLVANIA, JOINTLY AS TRUSTEES

ADJUSTABLE PITCH PROPELLER

Application filed April 9, 1930. Serial No. 442,801.

This invention relates to propellers for use in aeroplanes and in particular to mechanism for changing the pitch of the propellers while rotating or in motion.

5 An object of this invention is the provision of a pitch changing means for propellers that shall be simple in construction, comparatively inexpensive to manufacture and more efficient and positive in action than those here-
10 tofore proposed.

Other objects of the invention will, in part, be apparent and will, in part, be obvious from the following description taken in conjunction with the accompanying drawings.

15 The invention comprises the novel details of construction and combination of parts more fully hereinafter described and particularly pointed out in the claims.

In the accompanying drawings which form 20 part of the specification and in which like reference characters designate like parts in all the views;

Figure 1 is a partial view in section of a propeller hub and propeller blades rotatably 25 mounted thereon about their longitudinal axes, the section being taken along said longitudinal axes of the propellers;

Fig. 2 is a partial view in side elevation of the propeller mechanism arranged and constructed in accordance with the invention;

Fig. 3 is a fragmentary view in side elevation of the clamps shown in Figs. 1 and 2;

Fig. 4 is a view in section taken on line IV—
30 IV of Fig. 2;

Fig. 5 is a partial view in front elevation of the propeller mechanism shown in Fig. 2;

Fig. 6 is a view in longitudinal section of a detail embodied in the mechanism for re-
40 versing the propeller blades;

Fig. 7 is a partial view in rear or back elevation of the propeller mechanism shown in Fig. 5; and

Fig. 8 is a partial view in section of the mechanism shown in Fig. 7 taken on line VIII—VIII thereof.

In Fig. 1 of the drawings, a propeller hub 10 is shown on which propeller blades 11 are 50 rotatably mounted about their longitudinal

axes. The propeller blades 11 are held in place on the hub 10 by clamps 12.

The hub 10 is preferably made of a high grade steel possessing the necessary qualities of strength required of hubs employed in 55 aeroplane service. The hub in the process of manufacture is made from a solid forging of steel or an alloy and machined to provide a splined bore 13 for receiving the power or propeller shaft. The hub is bored also at 14, 60 the axis of which is at right angles to the splined bore 13. The portions of the hub 10, about the bore 14 is machined in order to provide cylindrical extensions 15 for supporting 65 the propellers 11.

When the propellers 11 are in operative position on the hub, the cylindrical extensions 15 extend into the bases of the propellers as shown in Fig. 1.

Adjacent to the bases of the cylindrical extensions 15 are annular flanges 16. These flanges are in abutting relation with annular flanges 17 formed on the propeller blades 11 when mounted in place on the extensions 15. The clamping members 19 and 20 are knurled 70 or roughened at 17' so that the clamps 12 and the flanges may be held together frictionally when the clamps are turned or oscillated to change the pitch of the propellers.

The clamps 12 are of the split ring type and 75 comprise two similar semi-circular members 19 and 20 (see Figs. 1 and 2) of substantially U-shape or channel shape in section.

Stated more specifically the semi-circular member 19 forming part of the clamp 12 includes annular depending flanges 21 and 22 and the member 20 includes annular depending flanges 23 and 24. The members 19 and 20 of the clamps 12 are held firmly in clamping relation or position by means of bolts 25 that extend through bosses or projections 26 and 27 formed integral with the members 19 and 20 of the clamps. The bolts may be tightened and drawn up into clamping position 90 by lock nuts 28.

Since each propeller blade 11 is attached to the hub by independent clamps 12, one blade may be removed from the hub without removing the other. Also each blade may be 100

individually adjusted without affecting or adjusting the other blade.

In order that the propeller blades 11 may be turned easily about their longitudinal axes, 5 anti-friction bearings are mounted on the hub 10 between the flanges 16 of the hub and the flanges 22 and 24 of the clamps 12 (see Fig. 1). The anti-friction bearings comprise a split ring 30 and a split ring 31 between 10 which an annular ring 32 is placed. The ring 32 carries anti-friction rollers 33. The split rings 30 and 31 are preferably made of hardened steel so that only a relatively small amount of wear will take place in operation 15 or service. The split rings 30 fit snugly against the flanges 16 of the hub and the split rings 31 fit snugly against the flanges 22 and 24 of the clamps 12. By providing a clamp ring such as shown in Fig. 1 of the drawings 20 and an anti-friction bearing of the type disclosed, any type of propeller 11 may be employed; that is, the propeller may be of aluminum or steel or any form of alloy and need not be specially designed to accommodate 25 the anti-friction bearing because the bearing is between one flange of the clamp and the flange on the hub and, therefore, does not come in contact with the propeller.

In the operation of aeroplanes, it is highly 30 desirable to adjust the pitch of the propellers to a relatively low angle while the plane is climbing out of the field or "taking-off". If the blades are set at a relatively low angle, it is possible for the plane to "take-off" in a 35 much shorter distance than if the propellers are set at a high pitch angle. If the blades are set at a relatively low angle or at an angle which will give a high rate of climbing, the plane cannot develop a high flying speed after it is in the air. It is also highly desirable in the operation of aeroplanes to be 40 able to adjust the propellers to a high or flying angle when the plane is in the air because a much higher speed may be obtained.

45 The ordinary propeller blades which are not adjustable as to the pitch angle are usually adjusted at an angle that will give fairly good climbing speed and fairly good flying speed. This pitch angle is obviously a compromise; that is, both the climbing speed and the flying speed of the plane is sacrificed in order to obtain climbing and flying speeds that are fairly satisfactory.

In order that the propeller 11 shown in the 50 drawings may be adjusted to a relatively low angle, when climbing or "taking-off", so that the plane may take off in a relatively short distance, and to a relatively high angle after the plane is in the air to obtain a high flying speed, each blade 11 is provided with a lever 35 that is pivotally mounted on the hub 10 at 55.

As shown in Fig. 5 of the drawings levers 35 are mounted on opposite sides of the hub and are so placed that they are statically in

balance with reference to the longitudinal axes of the hub bore 13.

The manner of attaching the levers 35 to the hub 10 is shown more particularly in Fig. 6 of the drawings. As there shown a hole or recess 37 is bored in the body of the hub and provided with internal screw-threads 38. The lever 35 has a stub shaft 39 formed integral therewith that extends into the bore or hole 37. The free end of the stub shaft 39 is provided with a washer 41. Washer 41 is prevented from moving off the end of the stub shaft 39 by means of a pin 42.

The stub shaft 39 is held in the position shown in Fig. 6 of the drawings by means of a bushing 43. Bushing 43 is disposed about the stub shaft 39 and between the washer 41 and the lever 35. By turning the bushing 43 into the hole or recess 37, the lever 35 is turnably mounted on the hub. This manner of attaching the lever 35 to the hub is indicated also in broken lines in Fig. 5 of the drawings. As shown in Fig. 6, the bushing 43 is provided at its upper end with a hexagonal nut 45 formed integrally with the bushing. By turning the nut 45 with a wrench or other suitable tool, the bushing may be positioned as shown in the drawings.

Each lever 35 is provided with a longitudinal slot 46 in which a pin 47 is disposed for movement back and forth along the slot. The pin 47 carries a nut or head 48 to steady the lever 35 as it oscillates about the stub shaft 39 and also to prevent the pin from moving out of the slot 46.

Pin 47 is attached to a worm 50 which is pivotally mounted on a stub shaft 51 that has screw-thread engagement with the hub 10. Worm 50 is provided with a plurality of tapped or screw-threaded holes 53, 54 and 55, each located at different radial distances from the center of rotation of the gear. The screw-threaded or tapped openings 53 to 55, inclusive, are tapped so as to receive or accommodate the pin 47. By placing the pin 47 in the desired tapped hole the arc through which the lever 35 oscillates may be varied according to the variations in pitch angle required to suit flying conditions and also according to the power characteristics and size of the particular motor employed.

The levers 35 are mechanically connected to the clamps 12 of the propellers by connecting links 59 such as illustrated in Fig. 4 of the drawings. The connecting links 59 have ball-and-socket connections with the lever 35 and the clamps 12.

The connecting link 59, as shown in Fig. 4, comprises two rectangular plates 60 and 61 having complementary spherical recesses 62 and 63 at one end and similar complementary spherical recesses 64 and 65 at the opposite end. The link 59, as shown in Fig. 4, is connected to lever 35 by a pin 66 that has screw-thread engagement with the lever. Pin 66

has a spherical head 67 that is nested in the spherical complemental recesses 62 and 63 of the plates 60 and 61.

The link 59 is connected to the clamp 12 by a pin 68 that has screw-thread engagement with a boss or lug 69 formed integral with the member 19 of the clamp as shown more particularly in Fig. 2 of the drawings. The upper end of the pin 68 is provided with a spherical head 70 that is nested in the spherical complemental recesses 64 and 65 of the link 59.

By means of the ball-and-socket connection of the links 59 to the levers 35 and the clamps 12, the propellers 11 may be caused to reciprocate through a predetermined angle as the links 35 are oscillated by the gear 50. The propellers when in one extreme position are in climbing or low angle position, and when in the other position are in flying or high angle position.

Gear 50 meshes with a worm 72 carried on a jack shaft 73. The jack shaft 73 is journaled in spaced lateral extending arms 74 and 75 of a U-shaped yoke 76. The yoke 76 is formed integral with the hub 10 as shown more particularly in Fig. 7 of the drawings. Jack shaft 73 carries a thrust bearing 77 between the worm 72 and the arm 75 of the yoke.

On one end of the jack shaft 73, a pinion 78 is fixedly mounted. Pinion 78 has spiral teeth thereon that mesh with a worm 80 mounted concentrically about the longitudinal axis of the splined bore 13 of the hub. The worm 80 is free to turn on a locking sleeve 81 (see Figs. 1, 2 and 8) which holds the worm in position on the hub 10. The locking sleeve 81 is disposed between the hub and the worm 80 and has screw-thread engagement with the hub at 83 as shown more particularly in Figs. 1 and 8. Locking sleeve 81 is provided with an annular shoulder 82 that bears against the worm 80 to hold it in place. An annular shoulder 84 on the sleeve bears against the end of the hub so that when the sleeve is turned into locking position, sufficient friction is developed between the hub and the shoulder 84 and the screw-threads 83 to hold the clamping sleeve in its operative position.

Worm 80 carries an annular brake drum 86 that is formed, preferably, as an integral part thereof. The brake drum 86 coacts with a brake band 87 that is secured to an annular brake shoe 88. Brake shoe 88 is pivotally mounted on a fork-like member 89 which in turn is pivoted on a stub shaft 90. The lower end of the fork-like member 89 is pivoted at 91 to a brake rod 92. The opposite end of the brake rod 92 is pivotally connected at 93 to a brake lever 94 that is pivoted on a fixed shaft or pivot 95.

In practice the brake lever 94 is mounted in the cockpit of the plane and is manually

operable by the pilot. When it is desired to change the pitch of the propellers, the pilot pulls the brake lever 94 in the direction of the arrow 96 whereupon the brake shoe 88 is actuated to a position in which the brake lining 87 frictionally engages the brake drum 86. The friction between the brake lining 87 and the brake drum 86 causes the form 80 to move relatively to the hub 10 as it rotates about the longitudinal axis of the splined bore 13. This relative movement between the worm 80 and the hub 10 is such that the hub rotates faster than the worm. For this reason the pinions 78 on the jack shafts 73 will be caused to roll by the worm 80. As the spiral pinions 78 roll, the jack shafts 73 will turn to thereby turn the worms 72 which, as stated herebefore, are in mesh with the worms 50.

As the worms 50 turn, the levers 35 are caused to oscillate by movement of the pins 47 in the longitudinal slots 46 of the levers 35. This oscillation of the levers 35 is transmitted to the clamps 12, and as the flanges 17 of the propellers frictionally engage the knurled surfaces 17' of the clamps 12, the propellers 11 will be turned in opposite directions about the longitudinal axes.

In order that the pilot or operator may know what the angular position of the blades is at any particular time, an indicator or pointer 100 is provided that cooperates with a graduated scale 101. The scale 101 may be calibrated in terms of pitch angle so that when the pointer or indicator 100 is adjusted to any particular division on the scale 101, the operator may know what the pitch angle of the propellers 11 is at any particular time.

The indicator or pointer 100 is operated by an annular ring 102 that moves longitudinally along the axis of the splined bore 13 of the hub as the clamps 12 turn about the longitudinal axes of the propellers 11. Movement of the annular ring 102 is transmitted to the pointer or indicator 100 through a link 103 which in turn is pivotally connected to a link 104. Link 104 is pivotally connected at 105 to the pointer or indicator 100.

The link 103 is biased towards engagement with the annular ring 102 by means of a spring 107 disposed about the link 103 and mounted in a sleeve or cylinder 108. The spring 107 operates between a closure 109 of the cylinder or sleeve 108 and a disc 110 secured to the link 103.

It may be assumed that the position of the pointer 100 as shown in Fig. 2 indicates the high pitch angle or flying angle of the propeller blades 11 and that the opposite end of the scale 101 represents the position the pointer 100 will take when the propellers 11 have been adjusted to a relatively low pitch angle or climbing angle. The climbing pitch angle of the propellers 11 may be designated on the scale 100 by the reference character C

and the high or flying pitch angle of the propellers may be designated by the reference character F.

In the operation of the mechanism whereby the pitch angle of the propellers 11 may be varied between climbing and flying pitch angles, respectively, the pilot or operator observes the position of the pointer 100 while the brake lever 94 is held in the position in which the brake is caused to engage the brake drum 86 of worm 80. When the pointer 100 is adjacent to the point F on the scale, the brake handle 94 is released whereby rotation of the propellers 11 about their longitudinal axes is stopped when in the high pitch angle or flying position.

To return or adjust the propellers 11 to the low pitch angle for climbing, the operator or pilot operates the brake lever 94 and holds it in braking position until the pointer 100 is adjacent to the point C on the scale 101. When the pointer reaches this position, the operator or pilot releases the brake handle 94 whereby the blades are stopped in their climbing or low pitch angle position. Obviously, the pilot may adjust the pitch angle to any intermediate value.

The annular ring 102 is mounted on legs 111, that move back and forth through slots or apertures 112 formed in stub shafts 113 (see Fig. 8). The stub shafts 113 have screw-thread engagement with lugs or bosses 114 formed integral with the hub 10. Stub shafts 113 carry rollers 115 that engage the underside of the brake drum 86. These rollers 115 prevent the worm 80 from sliding inwardly and longitudinally along the hub 10.

The inner ends of the legs 111 are bent at an angle so as to provide lateral extensions or feet 116. The extensions or feet 116 are yieldingly held into engagement with the links 59 by coil springs 117 located between the extensions or feet 116 and the stub shafts 113.

When the propeller blades 11 are rotated about their longitudinal axes by the levers 35, the links 59 will cause the legs 111 attached to the annular ring 102 to move in the slots or apertures 112 of the stub shafts 113. The direction in which the annular ring 102 moves is determined by the direction in which the links 59 move. The movement of the annular ring 102 is transmitted to the link or rod 103 whereby the pointer 100 is caused to move to indicate the pitch angle of the propellers 11.

In order to follow through the operation of the adjustable pitch mechanism shown in the drawings, it may be assumed that the position of the levers 35, as shown in Fig. 2, is the position in which the propellers 11 are set or adjusted to the high or flying pitch angle. This is the angle to which the propellers 11 are adjusted when flying at any given altitude.

When the pilot is about to make a landing, the blades are adjusted to the low or climbing pitch angle, so as to decrease the speed of the plane.

To adjust the propellers 11 to the low or climbing pitch angle the brake handle 94 is operated in the direction of the arrow 96 so that the brake lining 87 carried by the brake shoe is actuated into braking engagement with the brake drum 86. The friction between the brake lining and the brake drum will cause the worm 80 to stop or approximately stop so that the pinions 78 will cause the worms 72 carried by the jack shafts 73 to turn the worms 50 in opposite directions. Only one of the worms 50 is shown in Fig. 2 of the drawings, but it is to be understood that the other worm 50 is on the opposite side of the hub. The worm 50 shown in Fig. 2 will turn in a counter-clockwise direction and cause the lever 35 to turn on its pivot 36 (that on the stub shaft 39 shown in Fig. 6) in a clockwise direction, thereby turning one of the propellers 11 in the direction indicated by the arrow 97. The worm 50 on the opposite side of the hub will turn its lever 35 in a clockwise direction, whereby the other propeller will be turned in the direction indicated by the arrow 98.

As the propellers 11 are turning in opposite directions about their longitudinal axes, the operator or pilot observes the position of the pointer 100 and when it reaches a point adjacent to division C on the scale 101, the brake is released to thereby stop the propellers 11 in the low or climbing pitch angle.

If conditions are such that the pilot cannot make a landing with the plane, he may then direct his plane upwardly to a higher elevation so that he may again prepare for a landing. Since the blades are in the climbing pitch angle, the motor may be running at or near its maximum speed so that it may develop its maximum power for climbing. This is an advantageous feature since it often happens that a pilot must make a very steep climb in order to avoid striking trees or other obstructions, and if the blades are in a high pitch angle this cannot be done.

If the pilot is able to make a landing, the propeller blades 11 are caused to remain in their low or climbing pitch angle so that the blades will be inclined at the proper angle for "taking-off" the field in case the pilot is to make another flight. It is to be understood at this point that the propellers 11 will always be set in the low or climbing pitch angle when the plane is to "take-off" the field.

If it is to be assumed that the plane has taken-off the field and has climbed to an altitude suitable for continuous flying, the pilot will operate the brake handle 94 so that the brake lining 87 will engage the brake shoe 86. The worms 50 will then be caused to turn in the same direction as in the case

where the pitch of the blades is adjusted to the low or climbing angle until the levers 35 have been oscillated to the position shown in Fig. 2 of the drawings. The propellers 5 11 will then be in the high or flying pitch angle. When the propellers are in the high or flying pitch angle, the motor may be slowed down to a speed far below its maximum speed. Even though the motor has 10 been slowed down to a value considerably below its maximum speed, the plane will move through the air at a high speed because the blades are set at a high pitch angle. This is a desirable feature of the invention 15 in that it saves unnecessary expenditure of power and wear and tear on the motor and the plane as a whole because the vibration of the motor will not be so great at the lower motor speeds.

20 Since the pitch of the propellers 11 may be varied between predetermined limits by means of a single brake mechanism, the operation of changing the pitch of the blades is very simple and is easily accomplished.

25 By the invention herein disclosed, the propeller blades 11 may be oscillated through a predetermined angle about their longitudinal axes by means of a single brake mechanism which is mechanically connected to the propeller blades in such a way that when the 30 brake is in braking position, the pitch angle of the propellers is varied and may be adjusted to the desired value. This adjustment is accomplished by a simple oscillating 35 mechanical mechanism and by means of which the pitch angle of the blades may be adjusted to either a high value or a low value according to the particular conditions to be met in flying.

40 While only one embodiment of the invention has been shown and described, it is to be understood that various modifications and changes may be made therein without departing from the spirit and the scope of the 45 invention. It is desired, therefore, that only such limitations shall be placed on the invention as are imposed by the prior art and the appended claims.

50 What I claim as new and desire to secure by Letters Patent is:

55 1. In combination with a propeller hub having a crank shaft bore therein and a propeller blade mounted on the hub and turnable about its longitudinal axis, of a lever pivotally connected to the hub and propeller, said lever having a longitudinal slot, a gear 60 turnably mounted on the hub, a pin on said gear extending into the slot of said lever, a jack shaft on said hub, a worm on said shaft meshing with said gear, a gear on said shaft, a worm on said hub mounted concentrically with the crank shaft bore thereof, said concentrically mounted worm 65 meshing with the jack shaft gear, a brake drum on said hub concentrically mounted

worm, a brake, and means for operating said brake into braking engagement with said drum, whereby when the hub is rotating, relative movement between the concentrically mounted worm and the hub is effected.

2. The combination with a propeller hub having a crank shaft bore therein, of a propeller blade mounted on the hub and turnable thereon about its longitudinal axis, a lever pivotally mounted on the hub and having one end pivotally connected to the propeller, and means for oscillating the lever in response to rotation of the hub about its crank shaft bore as an axis, whereby the pitch angle of said propeller is varied.

3. The combination with a propeller hub having a crank shaft bore therein, of a propeller blade mounted on the hub and turnable thereon about its longitudinal axis, a lever pivotally mounted on the hub and having one end pivotally connected to the propeller blade, means for oscillating the free end of said lever in response to rotation of the hub about its crank shaft bore as an axis, whereby the pitch angle of said propeller is varied and means for indicating the pitch angle of the propeller.

4. In combination with a propeller hub having a crank shaft bore therein and a propeller blade on the hub, said blade being turnable about its longitudinal axis, of a lever pivotally connected to the hub and the propeller, said lever having an elongated slot therein, a gear turnably mounted on the hub, a pin on said gear extending into the slot of said lever whereby upon rotating of said gear the lever is oscillated to oscillate the propeller through a predetermined pitch angle, and means for rotating said gear in response to rotation of the hub about the crank shaft bore as an axis.

5. The combination with a propeller hub having a crank shaft bore therein, of a propeller blade turnably mounted on the hub, an oscillatory lever pivotally connected to said hub and said propeller blade, a worm turnably mounted on said hub, said worm being concentric with said hub bore, a brake drum on said worm, means operable by said worm to oscillate said lever and turn said propeller through a predetermined pitch angle in response to relative movement between the hub and worm, and brake mechanism operable upon said brake drum to effect said relative movement.

6. In combination, a propeller hub having a propeller rotatably mounted thereon, means for oscillating said propeller through a predetermined pitch angle, and a single brake mechanism for operating said oscillating means while the propeller is in motion.

7. In combination, a propeller hub having an annular flange thereon, a propeller on said hub, said propeller having a flange abutting said hub flange, a two-part clamping

- ring having depending flanges straddling the hub and propeller flanges, an oscillatable lever mounted on the hub, said lever having a pivotal connection with said two-part 5 clamping ring, and a crank on said hub to oscillate the lever, thereby to vary the pitch angle of said propeller.
8. In combination, a propeller hub having an annular flange thereon, a propeller on said 10 hub, said propeller having a flange abutting said hub flange, a two-part clamping ring having depending flanges straddling the hub and propeller flanges, an oscillatable lever mounted on the hub, said lever having a pivotal connection with said two-part clamping ring, a crank pivotally mounted on said hub arranged to oscillate said lever, and means for, at will, providing a driving connection 15 between said hub, while rotating, and said 20 crank, thereby to turn said crank and effect an oscillating movement of said lever.
9. In combination, a propeller hub having an annular flange thereon, a propeller on said hub, said propeller having a flange abutting 25 said hub flange, a two-part clamping ring having depending flanges straddling the hub and propeller flanges, an oscillatable lever mounted on the hub, a link having a ball-and-socket connection with said lever 30 and said two-part clamping ring, and a crank turnably mounted on said hub to oscillate said lever, thereby to vary the pitch angle of said propeller.
10. In combination with a propeller hub 35 having a crank shaft bore therein and a propeller blade on the hub, said blade being turnable about its longitudinal axis, of a lever pivotally connected to the hub and the propeller, a crank turnably mounted on the hub 40 arranged to oscillate said lever, thereby to oscillate said propeller through a predetermined pitch angle, and means for turning said crank in response to rotation of the hub.
11. In combination, a propeller hub having 45 an annular flange thereon, a propeller on said hub, said propeller having a flange abutting said hub flange, a two-part clamping ring having depending flanges straddling the hub and propeller flanges, an oscillatable 50 lever mounted on the hub, a link having a ball-and-socket connection with said lever and said two-part clamping ring, a crank turnably mounted on said hub to oscillate said lever, thereby to vary the pitch angle 55 of said propeller, and means for, at times, establishing a driving connection between the hub and said crank when the hub is rotating about its crank shaft bore as an axis.
12. The combination with a propeller hub, 60 of a propeller blade mounted on said hub and turnable thereon about its longitudinal axis, an oscillatory member pivotally mounted on said hub and pivotally connected to said blade, a worm turnably mounted on 65 said hub and normally rotating therewith and means having a pin and slot connection with said member operable in response to relative movement between said hub and said worm for oscillating said member.
13. The combination with a propeller hub, 70 of a propeller blade rotatable thereon about its longitudinal axis, an oscillatory member pivotally mounted on said hub and pivotally connected to said blade, a worm turnably mounted on said hub and normally rotating 75 therewith, means for retarding the speed of rotation of said worm relative to said hub, and means operable by said worm having a pin and slot connection with said member for oscillating said member.
- In testimony whereof, I have hereunto subscribed by name this 5th day of April, 1930.
